UNITED STATES PATENT OFFICE

2,651,267

LATCHING MEANS FOR HOPPER CAR DOORS

George B. Dorey, Westmount, Quebec, Canada,
assignor to Enterprise Railway Equipment
Company, Chicago, Ill., a corporation of Illinois

Application January 5, 1950, Serial No. 137,016

10 Claims. (Cl. 105—308)

1

This invention relates to an improved latching means for a hopper car door such as employed in railway dump cars and the like.

Among the objects of this invention are: To provide improved latching means for latching the swinging edge of a pendantsly mounted hopper door to the sloping floor of a hopper in such a manner that the reaction incidental to the door closing operation will tend to draw the floor and door together; to provide a generally axially movable latching element for a pendantsly mounted door which will be biased for movement toward the hinge axis of the door; to provide an operating lever for such a latch element which will act as a counterbalance to bias it toward the pivotal axis of the door; to provide for displacing the latch element from biased position by a striker face disposed substantially parallel to the rail on which the car is mounted; and to provide a latch element having a wedge acting head co-operating with a wedge receiving aperture in which outward divergence of the sides is in a downward direction. This invention also resides in details of construction making for safety and convenience of operation.

For a more complete understanding of the nature and scope of this invention reference may be had to the following description taken together with the accompanying drawings, in which:

Figure 1 is a view, in front elevation, of the door of a hopper for a hopper type of car in which the present invention is embodied, the door being shown in pendant open position facing the opening with the hopper being shown between the center sill and side wall of a conventional type of railway car;

Figure 2 is a vertical sectional view of the door and hopper shown in Figure 1 as viewed on a line 2—2 of Figure 1;

Figure 3 is a vertical elevational sectional view at an enlarged scale taken generally along the line 3—3 of Figure 1 and showing the position of the door as the latch element contacts the striker face of the keeper;

Figure 4 is a vertical elevational sectional view similar to Figure 3 except that the door is shown in a further advanced state of closure with the door held in partly open position;

Figure 5 is a vertical sectional view similar to Figure 3 but showing the door in closed position;

Figure 6 is a front elevational view of a door and frame assembly in which this invention is embodied, the door being shown in latched position;

2

Figure 7 is a vertical side view of the assembly shown in Figure 6 as seen from left to right;

Figure 8 is a fractional view of Figure 6 showing the lower part of the door frame with the latch bar in released position;

Figure 9 is a top plan view of a latch operating lever;

Figure 10 is a view, in front elevation, of the lever shown in Figure 9;

Figure 11 is a top plan view of a door beam;

Figure 12 is a view, in front elevation, of the door beam shown in Figure 11;

Figure 13 is a detail sectional view taken generally along the line 13—13 of Figure 12;

Figure 14 is a view, in side elevation, of the latching bolt element;

Figure 15 is a view, in front elevation, of the latching bolt element shown in Figure 14;

Figure 16 is a top plan view of the keeper; and Figure 17 is a view, in side elevation, of the keeper shown in Figure 16.

In the drawings the invention is shown as applied to a W type of hopper railway car in which the doors extend transversely of the rails one of which is indicated at 10 in Figure 2. The reference character 11 designates a center sill of a conventional railway car having a side sill 12 spaced therefrom with a hopper 13 therebetween. The hopper 13 is formed by inner and outer

30 side walls indicated at 14 and 15 respectively, a top sloping floor 16 and a lower sloping floor 17 which slopes downwardly to an opening 18. Surrounding the opening 18 is a frame that is indicated generally at 19 in Figure 6. It comprises a lower portion 20 which overlies the respective side walls 14 and 15 and a transversely extending portion 21 which underlies the sloping floor 17. The lower portion 21 is preferably of angle shape having an outstanding wall 22. The upper part of the frame 19 includes a top beam member 23 from which hinge butts 24 project.

The hinge butts 24 carry hinge pins 25 which support hinge straps 26 at their upper ends. The hinge straps 26 are preferably secured by rivets

45 27 to the door proper which is indicated generally at 28. The door 28 is preferably of trapezoidal form and of pan shape and it has a flange 29 around its edge which fits over and encloses the four sides of the frame 19 so as to provide a tightly fitting joint between it and the door 28.

The door 28 is of the type which is adapted to be swung or lifted to closed position and latching means are employed to retain it in closed position. The latching means of this invention 55 includes a latching bolt element 30, Figures 14

3

and 15, which is pivotally connected at 31 to a lever 32, Figures 9 and 10 and is bodily movable generally endwise at right angles to the hinge axis of the door 28. The lever 32 in turn is pivotally mounted intermediate its ends as indicated at 33 on a door reinforcing beam 34, Figures 11, 12 and 13, which extends contiguously with and adjacent to the swinging edge of the door 28, as shown in Figures 1, 6 and 8.

The latching element 30 is preferably located midway of the door 28 and door opening 18 and is adapted to engage with a keeper indicated at 35, Figures 6, 8, 16 and 17, and which includes a body portion 35' secured to the lower floor 17 and to the lower portion 20 of the frame 19.

The latch element 30 is biased to move upwardly toward the hinge axis of the door 28. To this end the lever 32 is provided with arms of different lengths and weight, the short arm, indicated at 36, extending between the pivot 33 and the latch element 30 and the long arm, indicated at 37, extending outwardly from the pivot 33 toward the outer side wall of the hopper 13 and provided at its outer end with an outwardly extending operating head 38 whereby the lever may be operated. The long arm 37 with its associated operating head 38 thus provides an effective counterbalancing action for biasing the generally axially movable latch element 30 toward normal latching position and maintaining it in this position.

The portion of the latch element 30 which cooperates with the keeper 35 includes laterally extending head portions 39, Figures 14 and 15, which extend outwardly from each side of an elongated shank portion 40 and in combination with the latter form a T-shaped configuration.

The laterally extending head portions 39 are received in an aperture 41, Figure 16, formed in the keeper 35. As there shown, the aperture 41 is T-shaped and includes a central opening or slot 42 for the accommodation of the shank portion 40 of the latch element 30. At each side of the aperture or slot 42 there is a shouldered face including shoulders or steps arranged in advance of each other as indicated at 43 and 44 respectively, Figure 17, and which are connected by an inclined wedging surface 45.

The outer face of the head portions 39 of the latch element 30 is similarly formed with stepped shoulders 46 and 47, Figures 14 and 15, connected by an inclined wedging surface 48 to provide a contour adapted to register with the contour provided by the steps 43 and 44 and interconnecting surface 45 of the keeper 35.

In order to bring the respective engaging faces of the latching bolt element 30 and the keeper 35 into coacting engagement, the former is displaced from its normal latching position by having the upper inner face 49 of each head portion 39 engage the inclined striker surface 50 of the nose 51 of the keeper 35 as shown in Figure 3. It will be noted that, although the striker surface 50 is inclined in relation to the path of movement of the latching bolt element 30, this surface is disposed substantially in parallelism with the rail 10, Figure 2, and therefore it does not encroach unduly on the allowable clearance limits of the car structure.

The door beam 34, which forms the support for the latch operating lever 32 is preferably of angle shaped formation with one wall 52, Figure 11, secured to the body of the door 28 and the adjacent wall 53 outstanding therefrom. The beam 34 is provided with an upstanding wall 54 which is in

combination with wall 52 constitutes a pair of walls between which the latch operating bar or lever 32 is mounted and which supports the pivot 33. Intermediate the pivot 33 and the outer edge of the door 28 the beam 34 is formed with a pair of spaced walls including an inner wall 55 and an outer wall 56 between which the long arm 37 is guided in its swinging movement. Disposed between the walls 55 and 56 is a locking dog 57 which is pivotally mounted at 58 to swing in the path of movement of the lever 37 and lock the same in closed position.

The outstanding wall 53 of the beam is apertured, as indicated at 59, to accommodate the shank portion 40 of the latching element 30 therethrough and a reinforcement 60 surrounds this opening. Formed integrally with the beam 34 is a depending portion 60a, Figure 13, which contacts with and forms a support for the inner face 61 of the latch bolt element 30.

An open ended pocket 62, Figures 7 and 12, is provided below the outstanding wall 53 for the purpose of accommodating one end of a removable operating bar to swing the door 28 closed. The pocket 62 is formed integrally with the outstanding wall 53 of the beam 34.

The construction including a relatively short lever arm 36 on which the latch element 30 is mounted provides a wide degree of swing thereof in its movement between extreme positions. In order to facilitate the operation of the latch element 30 I provide fulcrum seats of arcuate shape formed on large radii to form seats on which removable levers may rock. These fulcrums will now be described.

The extreme outer end of wall 53 of the beam 34 adjacent the outer side wall of the hopper 13 is curved downwardly as shown at 63 in Figure 8 to form a fulcrum and receive an operating bar 64 for prying the operating head 38 of the latch arm 37 upwardly to release or unlock the door 28. Similarly a curved fulcrum seat 65 is provided on the outer guiding wall 56 for the purpose of providing a rest for the operating bar 64 for levering the long arm 37 of the lever 32 to move the latch bolt 30 to final latching position.

In operation, assuming the door 28 to be in the open position as shown in Figures 1 and 2 with the latching bolt 30 biased to normal latching position, the door 28 is moved toward closed position by inserting one end of the bar 64 in the socket 62 and swinging the other end from a position beyond the side wall 12. The face 49 of the latch element 30 engages the striker face 50 of the keeper 35 as shown in Figure 3. Continued movement of the door 28 effects a downward displacement of the latch element 30 until the end of the surface 50 is reached. Then the latch element 30 moves generally axially upwardly under the biasing action of the weight of the long arm 37, bringing the upper shoulder 46 into engagement with the shoulder or step 43 of the keeper 35. The door 28 now is retained in partially closed position as indicated in Figure 4.

The operator then bears down on the outer end of the long lever arm 37, using the bar 64 if necessary to obtain multiplied leverage and completes the final movement of the latching element 30 to the fully latched position as shown in Figure 5. The downward movement of the outer end of the lever 37 has the effect of exerting a downward pull on the door 28 and, because of the engagement with the inclined surface 45, an upward reaction on the lower sloping floor 17 thus tending to maintain these two components in close rela-

tion and effectively guarding against sagging of the floor 17 both during the door closing operation and after the door 28 is fully closed and the locking dog 57 is operated to the locked position.

It will be noted that the application of the force tending to exert a downward pull on the door 28 as just described is exerted at an appreciable distance outwardly of the hinge axis of the door 28 and outwardly of its center of gravity. This relationship provides a favorable turning moment on the door 28 toward closed position as indicated by the reference character 67 in Figure 2.

It will be understood that sufficient clearances are provided between the latching bolt element 30 and the parts associated therewith so that the former can move between the positions shown in Figures 6 and 8 without interference. For example, the opening in the lever 32 for receiving the pivot pin 31 can be substantially greater in diameter than that of the pin 31 or this opening can be slotted along the longitudinal axis of the lever 32. In addition clearance between the sides of the element 30 and the adjacent surfaces of the aperture 59 in the door beam 34 and the central opening 42 in the keeper 35 is provided in accordance with customary manufacturing tolerances.

Since certain further changes may be made in the above construction and different embodiments of the invention may be made without departing from the scope thereof, it is intended that all matter contained in the above description or shown in the accompanying drawings shall be interpreted as illustrative and not in a limiting sense.

What is claimed as new is:

1. In a latching means for the door of a hopper railway car having a discharge opening and a door pivotally mounted adjacent the upper part of the opening to assume a pendant open position, the improvement in means for latching the door in closed position, including a keeper carried by the hopper and located adjacent the swinging edge of the door, an elongated latch element carried by the door and bodily movable generally endwise at right angles to the hinge axis of the door for cooperating with said keeper for latching the door in closed position, means biasing said latch element to move upwardly, and interengaging parts on said keeper and latch element cooperating on closing of the door to move said latch element downwardly until the same clears said keeper whereupon said biasing means moves said latch element upwardly into latching position with said keeper.

2. In a latching means for the door of a hopper railway car having a discharge opening and a door pivotally mounted adjacent the upper part of the opening to assume a pendant open position, the improvement in means for latching the door in closed position including a keeper carried by the hopper and located adjacent the swinging edge of the door, an elongated latch element carried by the door and bodily movable generally endwise at right angles to the hinge axis of the door for cooperating with said keeper for latching the door in closed position, a lever pivotally mounted intermediate its ends on the door to provide oppositely extending arms, means pivotally connecting one of said arms to said latch element, the other of said arms being weighted to bias the companion arm and said latch element upwardly toward the hinge axis of the door, and interengaging parts on said keeper and latch element cooperating on closing of the door to move said latch element downwardly until the same

clears said keeper whereupon said weighted arm moves latch element upwardly into latching position with said keeper.

3. In a latching means for the door of a hopper railway car having a discharge opening and a door pivotally mounted adjacent the upper part of the opening to assume a pendant open position, the improvement in means for latching the door in closed position including a keeper carried by the hopper and located adjacent the swinging edge of the door, an elongated latch element carried by the door and bodily movable generally endwise at right angles to the hinge axis of the door for cooperating with said keeper for latching the door in closed position, a lever pivotally mounted intermediate its ends on the door to provide oppositely extending arms, means pivotally connecting one of said arms to said latch element, the other of said arms being weighted to bias the companion arm and said latch element upwardly toward the hinge axis of the door, and interengaging parts on said keeper and latch element cooperating on closing of the door to move said latch element downwardly until the same clears said keeper whereupon said weighted arm moves said latch element upwardly into latching position with said keeper, said interengaging parts on said keeper and latch element having stepped engaging faces connected by an inclined wedging face for maintaining the door in either a partly closed or fully closed position whereby movement of said latch element from partly to fully closed position of the door along said wedging face exerts a pull on the door away from its hinge axis and exerts a turning movement on the door in the closing direction.

4. In a hopper having a discharge opening and a door pivotally mounted adjacent the upper part of the opening to assume a pendant open position, the improvement in means for latching the door in closed position including an elongated latch element carried by the door and bodily movable generally endwise at right angles to the hinge axis of the door and a coacting shouldered keeper carried by the hopper and having a projecting nose portion extending beyond the door in closed position, and means biasing said latch element to move upwardly towards the pivotal axis of the door to a latching position, said latching element having a shank portion and laterally extending head portions providing an inverted T-shape and adapted first to contact said nose portion of said keeper to displace said latching element downwardly from said latching position upon movement of the door to closed position, said latching element thereafter being moved upwardly by said biasing means to cause said head portions to engage with the shouldered part of said keeper and hold the door closed.

5. In a railway car including a hopper having a discharge opening extending transversely across a rail on which the car is mounted, said hopper including a sloping floor for directing lading to the discharge opening and a door pivotally mounted adjacent the upper part of the opening and arranged to assume a pendant open position and movable to closed position to meet with the lower margin of the sloping floor; the improvement in latching means for retaining the door in closed position which includes interengaging latch elements carried by the floor and door respectively, the latch element carried by the floor including a keeper having a shoul-

dered face and a projecting nose portion extending beyond said face including a lower surface extending substantially parallel to the rail and inclined to the plane of the discharge opening, and the element carried by the door being an elongated latch element bodily movable generally endwise at right angles to the hinge axis of the door and provided with a shank and laterally extending shouldered means at the lower end adapted to engage said shouldered face of said keeper in latching position, and means biasing said latch element to move upwardly towards the pivotal axis of the door to said latching position, said laterally extending shouldered means being adapted to ride in contact with said lower surface of said nose portion of said keeper to displace said latch element downwardly from said latching position on movement of the door to closed position whereby said shouldered means clears said nose portion and thereupon is moved upwardly by said biasing means to engage said shouldered face and hold the door closed.

6. In combination with a pivotally mounted hopper car door of the type adapted to assume an open pendant position and movable to an inclined closed position, latching mechanism for the door including a lever pivotally mounted thereon to swing in a plane substantially parallel thereto, said lever being extended to a location adjacent a side edge of the door and there provided with an outwardly extending operating head, a beam extending along the swinging edge of the door, said beam being angularly shaped with one flange outstanding from the door, said flange being disposed in the plane of said operating head of the lever and formed with a downwardly curved outer portion spaced from said operating head to form a seat for an operating bar whereby the same may be inserted between said seat and said head of said lever for raising the latter.

7. In combination with a pivotally mounted hopper car door of the type adapted to assume an open pendant position and movable to an inclined closed position, a latch bar pivotally mounted on the door to swing in a plane parallel with the plane thereof, and having an operating head outstanding therefrom, a guide wall overlying said latch bar, and a seat outstanding from said guide wall, said seat being a wall of arcuate contour having an appreciable radius to form a seat for receiving a removable operating bar for cooperation with said operating head to release said latch bar.

8. In a railway car including a hopper having a discharge opening, a sloping floor for directing lading thereto, and a door hinged adjacent the upper side of the opening and arranged to assume a pendant open position and to be swung to closed position to meet with the lower margin of the sloping floor; latch means for holding the door closed and preventing separation of the lower margin of the sloping floor therefrom including a keeper carried by the floor along its lower margin and having stepped shoulders extending in planes generally at right angles to the plane of the floor and interconnected by a wedging surface facing generally downwardly, an elongated latching element endwise slidably mounted on the door along its swinging edge for movement toward and away therefrom at right angles to the hinge axis of the door and hav-

ing stepped shoulders interconnected by a wedging surface facing generally upwardly, and a lever pivoted on the door and connected to said latching element for moving the shoulders and 5 wedging surface thereof into engagement with the shoulders and wedging surface on said keeper when the door is closed.

9. In a railway car including a hopper having a discharge opening, a sloping floor for directing lading thereto, and a door hinged adjacent the upper side of the opening and arranged to assume a pendant open position and to be swung to closed position to meet with the lower margin of the sloping floor; latch means 10 for holding the door closed and preventing separation of the lower margin of the sloping floor therefrom including a keeper carried by the floor along its lower margin and having stepped shoulders extending in planes generally at right angles to the plane of the floor and interconnected by a wedging surface facing generally downwardly, said keeper having a nose portion extending beyond said shoulders and wedging surface and having a striker surface facing generally downwardly, an elongated latching element endwise slidably mounted on the door along its swinging edge for movement toward and away therefrom at right angles to the hinge axis of the door, and means biasing said latching element to move 15 upwardly towards the pivotal axis of the door, 20 said latching element having a surface facing upwardly for engaging said striker surface when the door is swung to closed position to displace said latching element so that the same clears said nose portion of said keeper, said latching element also having stepped shoulders interconnected by a wedging surface facing generally upwardly for engaging the shoulders and wedging surface on said keeper under the action of said biasing means when the door is closed and said latching element has been displaced as aforesaid.

10. In a latching means for the door of a hopper railway car having a discharge opening and a door pivotally mounted adjacent the upper part of the opening to assume a pendant open position, the improvement in means for latching the door in closed position including a keeper carried by the hopper and located adjacent the 25 swinging edge of the door, said keeper having a shoulder engageable from its underside and having on its underside a striker surface leading to said shoulder, and an elongated latch element carried by the door and bodily movable generally endwise at right angles to the hinge axis of the door for cooperation with said keeper, said latch element having a portion engageable with said striker surface on closing of the door to displace said latch element downwardly into registration with said shoulder whereupon said latch element is movable upwardly to place another portion thereof in locking engagement with said shoulder.

GEORGE B. DOREY.
